UPPER BODY ELEMENT FOR A TOY FIGURE

Jens Nygaard Knudsen, Billund, and Leif Justesen, Give,
Denmark, assignors to Interlego A.G., Zug, Switzerland

Filed Dec. 3, 1974, Ser. No. 529,028

Term of patent 14 years

Int. Cl. D21—01

U.S. Cl. D34—15 GG

Fig.4

Fig.2

Fig.3

Fig.1

FIG. 1 is a perspective view of an upper body element for a toy figure showing our new design;

FIG. 2 is a front elevational view;

FIG. 3 is a bottom plan view; and

FIG. 4 is a side elevational view thereof.

We claim:

The ornamental design for an upper body element for a toy figure, as shown and described.
